UNITED STATES PATENT OFFICE.

CHARLES B. EYER, OF CLEVELAND, OHIO.

CRUDE-OIL BURNER.

Application filed June 28, 1921. Serial No. 481,043.

To all whom it may concern:

Be it known that I, CHARLES B. EYER, a citizen of the United States, residing at Cleveland, in the county of Cuyahoga and State of Ohio, have invented certain new and useful Improvements in a Crude-Oil Burner; and I do hereby declare the following to be a full, clear, and exact description of the invention, such as will enable others skilled in the art to which it appertains to make and use the same.

This invention relates to vapor burners and aims to devise an article of this nature which will admit of the successful use of crude oil as fuel without obstructing the flow of the oil and vapors by accumulations of carbon in the various pipes after the burner has been in operation for a comparatively short time.

The invention contemplates a fan in conjunction with the burner to insure a distribution of the heat and a second fan for agitating the air and vapors to thoroughly mix the same.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the nature of the invention.

Referring to the accompanying drawings forming a part of the specification,

Figure 1 is an elevation of a burner constructed in accordance with an embodying the essential features of the invention.

Figure 2 is a vertical central section thereof.

Fig. 3 is a front view showing the valve more clearly, and

Figure 4 is a top plan view the upper fan being omitted.

Corresponding and like parts are referred to in the following description and designated in the several views of the drawings by like reference characters.

The burner comprises a plate 1 which forms supporting means for the cooperating parts. An opening 2 is formed in the plate 1 and a collar 3 surrounds the opening 2 and projects upwardly from the plate 1. A chamber 4 depends from the plate 1 in line with the opening 2 and is provided centrally

of its bottom with a depending bracket 5 in which is set a vertical shaft 6, the latter passing through an opening formed in the bottom of the chamber 4 in line with the bracket 5. The chamber 4 has a lateral extension 7 disposed beneath an edge portion of the plate 1. A casing 8 is disposed at the opposite side of the chamber 4 from the lateral extension 7 and is attached to the plate 1. Valves 9 of the needle type are disposed within the casing 8 and control the feed of the fuel to the burner. A connection 10 joins the casing 8 and chamber 4 and is adapted to receive the air and fuel which mix therein prior to entering the chamber 4. A horn or tube 11 depends from the connection 10 and is in communication therewith, said horn tapering in its length with its enlarged end facing downward. The horn or tube 11 gathers and supplies air to the connection 10. The vaporized fuel escaping from the nozzle of the valve mechanism passes rapidly through the connection 10 into the chamber 4 and across the upper or delivery end of the horn 11 thereby creating a suction in the horn which insures a positive supply of air. The connection 10 constitutes in effect a preliminary mixing chamber in which the air and vapor mix. The air and gas pass from the part 10 into the chamber 4 and expand and further combine or mix. The part 4 therefore constitutes an expanding and mixing chamber.

A flared ring 12 is disposed upon the plate 1 and its lower contracted end is fitted to the collar 3. This flared ring constitutes the body of the burner proper. The burner cap 13 consists of a plate or disk fitted to the upper end of the flared ring 12 and having radially disposed flutes or corrugations in which are formed transverse slits or openings 14 constituting outlets for the gas. The shaft 6 projects above the part 13 and carries a fan 15 which acts to distribute the heat from the burner when the device is in operation. A second fan 16 is secured to the shaft 6 and is disposed within the chamber 4 and operates to agitate the air and gas whereby to thoroughly mix the same. The liquid fuel, such as crude oil, is supplied to the burner by means of a feed pipe 17 which cooperates with the valve mechanism 9.

The feed pipe 17 passing through the chamber 4 and its extension 7 is heated by the flame of the burner which materially assists in vaporizing the fuel which, as herein

stated, is discharged into the part 10 and the chamber 4. The gas passing through the chamber 10 mixes with the air drawn into said chamber through the horn or tube 11, 5 the air and gas passing from the chamber 10 into the chamber 4 in which they expand and are further mixed by the action of the fan 16. The gas escaping through the outlets 14 is ignited and the heat resulting 10 from the flame is distributed by the action of the fan 15.

Having thus described the invention, what I claim is:—

1. In a fuel burner of the character specified, a burner cap, a mixing chamber in line with the burner cap, means for supplying a gaseous mixture to the chamber, and a fan in said chamber for agitating the gaseous mixture.

2. In a fuel burner of the character specified, a burner cap, a mixing chamber in line with the burner cap, means for supplying a gaseous mixture to the chamber, a fan in said chamber for agitating the gaseous mixture preliminary to its consumption at the outlet of the burner, and a second fan in line with and spaced from the burner cap for spreading and distributing heat resulting from the consumption of the fuel.

3. In a fuel burner of the character specified, a burner cap, an expanding and mixing chamber in communication with the burner, a mixing chamber in communication with the expanding chamber, a lateral horn connected with the mixing chamber, and means for supplying fuel and delivering the same across the said horn to draw air therethrough for mixing with the fuel preliminary to the discharge of the latter into the expanding 40 chamber.

4. A fuel burner of the character specified comprising a burner cap, an expanding and mixing chamber in communication with the burner and having a lateral extension, a diametrically disposed casing, a valve mecha-

nism within said casing for controlling the supply of fuel, a mixing chamber forming connecting means between said casing and the expanding and mixing chamber, and a horn connected with the mixing chamber. 50

5. A fuel burner of the character specified comprising a burner cap, an expanding and mixing chamber in communication with the burner tip and having a lateral extension, a diametrically disposed casing, a valve mechanism within said casing for controlling the supply of fuel, a mixing chamber forming connecting means between said casing and the expanding and mixing chamber, and a horn connected with the mixing chamber, 60 a fan within the expanding and mixing chamber, and a second fan beyond the burner cap and connected with the fan in the expanding and mixing chamber and serving to distribute and spread the heat. 65

6. A fuel burner of the character specified comprising a burner cap, an expanding and mixing chamber in communication with the burner and having a lateral extension, a diametrically disposed casing, a valve mechanism within said casing for controlling the supply of fuel, a mixing chamber forming connecting means between said casing and the expanding and mixing chamber, a horn connected with the mixing chamber, a fan within the expanding and mixing chamber, a second fan beyond the burner cap and connected with the fan in the expanding and mixing chamber and serving to distribute and spread the heat, and a fuel feed pipe 70 passing through the expanding and mixing chamber and the extension thereof and having connection with the said valve mechanism. 75

In testimony whereof I affix my signature 80 in presence of two witnesses.

CHARLES B. EYER.
